UNITED STATES PATENT OFFICE.

RICHARD VARLEY, OF ENGLEWOOD, NEW JERSEY, ASSIGNOR TO VARLEY DUPLEX MAGNET COMPANY, A CORPORATION OF NEW JERSEY.

CIRCUIT BREAKER AND CONTROLLING MECHANISM.

Application filed September 18, 1919. Serial No. 324,450.

To all whom it may concern:

Be it known that I, RICHARD VARLEY, a citizen of the United States, residing at Englewood, in the county of Bergen and State of New Jersey, have invented certain new and useful Improvements in Circuit Breakers and Controlling Mechanism, of which the following is a full, clear, and exact description.

- 10 The principal application of my invention is to the internal combustion engines of automobiles, and it relates particularly to means for controlling the ignition circuit of such engines. More especially it relates to 15 means for controlling the breaker system in the ignition circuit either to regulate the occurrence of the spark in the cycle of the engine, or to regulate the relation between the periods of open and closed condition of the 20 breaker contacts for each actuation of the cam follower, or to effect both regulations.

The occurrence of the spark is ordinarily regulated by relatively angularly adjusting the breaker cam and cam follower concentrically with the cam, that is, about the axis of the cam as a center, the spark being advanced as the speed of the engine increases.

The length of time that the breaker contacts are left closed for each actuation of the cam follower is known as the electrical dwell, and manifestly this dwell must be for a sufficient period to properly energize the spark coil. In practice this dwell should be 35 substantially constant at all engine speeds, and for this purpose the duration of the open condition of the contacts must be relatively less at high engine speeds than it is at low engine speeds.

40 An object of my invention is to provide suitable automatically controlled means responsive to the speed of the engine for altering the angular relation of the cam and cam follower to effect the regulations referred to.

Still other objects and advantages of my invention will appear from the following description.

In accordance with my invention the 50 breaker system is mounted on a turn table or other adjustable support, and suitable automatic means responsive to the speed of the engine are employed to effect the desired adjustment. If it is desired to regulate the occurrence of the spark only the

turn table is pivoted concentrically of the cam, while if it is desired to regulate the relative duration of electrical dwell, the turn table is pivoted eccentrically of the axis of the cam, as is disclosed, for example, in the 60 co-pending application of James C. Anderson, filed August 22, 1919, Serial Number 319,092. As an instance of means for actuating the turn table responsive to the speed of the engine, I may employ the liquid friction transmission device disclosed in my co-pending application filed August 1, 1919, Serial Number 314,643.

My invention also includes other features of construction and arrangements of parts 70 as will hereinafter more fully appear.

I shall now describe the illustrated embodiments of my invention and shall thereafter point out my invention in claims.

Fig. 1 is a central sectional elevation of 75 one embodiment of my invention;

Fig. 2 is a plan of the same with the cover removed;

Fig. 3 is a plan of a different embodiment 80 of my invention;

Fig. 4 is a longitudinal sectional elevation of the same;

Fig. 5 is a horizontal section of the same;

Fig. 6 is a plan of the governor and associated parts in position of rest; 85

Fig. 7 is a similar view showing the position assumed by the parts when the governor is rotating;

Fig. 8 is a bottom plan of the parts as 90 shown in Figure 6;

Fig. 9 is a similar view of the parts as shown in Figure 7;

Fig. 10 is a sectional detail on line 10—10 of Figure 5; and

Fig. 11 is a plan of still another embodiment of my invention. 95

In the construction illustrated in Figures 1 and 2 the automatic adjustment serves only to advance or retard the spark. The transmission responds to the speed of the engine 100 and adjusts the angular position of a turn table on which the breaker system is mounted, and which is pivoted concentrically of the breaker cam shaft. The type of transmission selected for illustration is that described and claimed in my co-pending application, Serial Number 314,643.

A vertical operating shaft 1 of the transmission is driven from the engine and carries the breaker cam 2 on its upper end. 110

The primary member of the liquid friction drive comprises an annular metallic cup-shaped member 3 secured axially upon the shaft 1 immediately above an antifriction bearing from which it is spaced by a narrow collar. The secondary member 4 rests on top of the primary member and is an annulus provided at its inner edge with a hub portion which loosely surrounds the center portion of the primary member, and therefore is free to turn thereon. A suitable cover 5 encloses the device.

The primary member 3 is provided with a plurality of concentric flanges 3^a intermediate of which are similar depending flanges 4^a on the secondary member. The device is partially filled with oil or other liquid which serves to couple the two members and transmit a torque to the secondary member.

As in the construction of my said co-pending application the primary member carries the fier of the distributor system while the stationary radial contacts are carried by the stationary housing. This stationary distributor member is carried by a metallic base 6 and comprises a cylindrical or cup-shaped external shell 7 of bakelite or other insulating material in which are the distributor contacts 8. The fier distributor member 9 is also an annulus of bakelite or the like which is provided with a conducting ring 10 on its bottom edge, the fier 11 extending up therefrom into co-operative relation to the stationary contacts 8. Current is conducted to the ring 10 by a brush 12. While the base 6 and the parts carried thereby are stationary in the operation of the device, they are manually angularly adjustable relative to the internal rotative parts through the manipulation of a link 13 for a purpose which will hereinafter appear.

The stationary contact member 14 and the movable contact member 15 with its cam follower 16 are carried by a turn table 17 pivoted concentrically of the shaft 1. It is therefore evident that any angular adjustment of the turn table correspondingly varies the occurrence of the spark. The cam 2 is rotated clockwise as viewed in Figure 2, and a counter-clockwise adjustment of the cam follower advances the spark while a clockwise adjustment retards the spark. This adjustment of the turn table is automatically effected by the liquid transmission device.

In the construction shown a gear wheel 18 is secured to the top face of the hub portion 60 of the secondary member 4 and meshes with a segmental gear member 19 which has an outwardly extending arm pivoted to the shell 7 and carries an upwardly extending operating pin 20 in the end of the arm outside the pivot. This pin 20 engages in a slot

in an outwardly projecting portion in the turntable 17, the shell 7 being cut away to receive these operating projecting portions of the segment and turntable. The segment 19 and its co-operating parts are biased by a coil spring 21 which connects at one end to the segment and at the other end to the shell 7, the bias being in the direction for moving the turntable 17 to the position of greatest retard of the spark. A suitable cover 22 completes the device.

The torque of the secondary member increases with the speed of the primary member. The transmission will be so regulated that at low engine speeds the torque of the secondary member will not be sufficient to overcome the tension of the spring 21. As the engine speeds up the primary member exercises more and more drag upon the secondary member with the result that the gear wheel 18 and the segment 19 are rotated more and more in a clockwise direction against the tension of the spring 21. This movement of the segment 19 on its pivot rotates the turntable 17 in a counter clockwise direction through the engagement of the pin 20 in the slot in the turntable, and the cam follower 16 is correspondingly rotated in a counter clockwise direction and the spark is accordingly advanced. As the engine slows down and the drag upon the secondary member decreases, the spring 21 retracts the segment 19 and rotates the turntable 17 in a counter clockwise direction, thereby retarding the spark.

If it is desired to modify this automatic adjustment of the spark, the link 13 is manually operated to angularly adjust the shell 7 about the shaft 1. This adjustment serves to move the pivot of the segment 19, 105 the fulcrum being at the point of engagement of the gear teeth. The pin 20 is moved with the pivot and the turntable 17 is correspondingly adjusted. If it is desired to subtract from the automatic spark advance, the shell 7 is moved in a clockwise direction as viewed in Figure 2, while the shell is moved in the opposite direction to add to the automatic advance of the spark.

In the construction shown in Figures 3 to 10, inclusive, the liquid transmission device and the breaker system are on separate parallel shafts driven from a common countershaft. The turntable carrying the breaker system is pivoted eccentrically on the axis 120 of the cam, the pivot being so located that the movement of the operating face of the cam follower is along an oblique line at substantially the same angle to the tangent to the cam periphery as is the leading face 125 of the cam, with the result that the adjustment of the turntable merely serves to regulate the electrical dwell without affecting the occurrence of the spark. To control the spark occurrence governor controlled means 130

are provided for rotating the cam upon its axis relative to the cam follower.

The breaker cam shaft 23 which carries the cam 2 on its upper end, and the transmission drive shaft 1 are coupled to be driven from an engine driven countershaft 24 bearing in the ends of a suitable casing 25. The shaft 24 is surrounded internally of the casing by a sectional sleeve, the end 10 sections 26 and 27 of which are preferably fixed to the shaft to rotate with the shaft, and abutting against these sections are two worm sections 28 and 29 which are provided with worms 30 and 31 respectively. The 15 central clutch sleeve section 32 couples the worm sections 28 and 29 and is rotatively connected to the countershaft 24 by a pin 33 which is best shown in Figure 10. Through these connections the rotation of 20 the shaft 24 is transmitted to the worms 30 and 31. The worm 31 meshes with the worm wheel 34 on the drive shaft 1 and the worm 30 meshes with the worm wheel 35 on a sleeve 36 surrounding the lower end of the 25 cam shaft 23. The rotation of the shaft 24 is thus transmitted to the sleeve 36 which is coupled to the cam shaft 23 through the governor mechanism which will now be described.

30 The sleeve 36 carries on its upper end an irregularly shaped plate 37 which carries three laminated centrifugal weights 38, the top lamination being somewhat longer than the lower one. These weights are pivoted 35 on pins 39 carried by the plate 37, and are normally held in their contracted positions shown in Figures 6 and 8 by coil springs 40 which at one end engage pins 41 on the under side of the plate 37 and at their other 40 ends engage pins 42 carried by the weights, one of which pins 42 extends through an opening provided in the plate 37 which is large enough to permit the centrifugal movement of the weight, while the other 45 two pins 42 operate in recesses cut in the plate 37. The lower lamination of the weights are shaped to engage over the teeth of a three toothed gear member 43 which is carried by the cam shaft 23.

50 As the sleeve 36 is rotated the centrifugal weights carry with them the gear member 43 through the connection above described, and the cam shaft and cam are thereby rotated. When the speed of the engine rises 55 sufficiently to cause the centrifugal force of the governor weights to overcome the tension of the springs 40, the weights fly out as shown in Figure 7 and this movement imparts an angular movement to the gear 60 43 and hence to the cam 2, and it is this movement which automatically regulates the occurrence of the spark.

Manually controlled means are provided for adding to or subtracting from this automatic adjustment of the cam. For this pur-

pose, in the construction shown, a longitudinally adjustable collar 44 surrounds the clutch section 32 of the sleeve, and carries the pin 33 which rotatively secures the sleeve section and shaft 24. To permit of the longitudinal adjustment of the collar 44, the shaft 24 is provided with a longitudinal axial slot 45 and the sleeve section 32 is provided with a longitudinal oblique slot 46, as shown particularly in Figure 5. It 70 is manifest that as the pin 33 is shifted by the adjustment of the collar 44, the sleeve section 32 will be rotated upon the shaft 24 and thus manual rotation of the sleeve section 32 will be transmitted through the 80 worm 30, worm wheel 35, sleeve 36 and governor mechanism of the cam shaft 23 and cam 2.

To longitudinally adjust the collar 44 upon the sleeve section 32 a transverse rock 85 shaft 47 is provided above the sleeve 32 and bearing in the side walls of the casing 25. A manually controlled crank 48 is fixed on one end of the rock shaft 47 outside of the casing. A yoke or fork member 49 is carried by the rock shaft and has two opposite inwardly projecting fingers which engage between the flanges of the collar 44. Actuation of the crank 48 thereby serves to adjust the collar 44 and manually regulate the 95 occurrence of the spark.

The shafts 1 and 23 bear at the lower ends in suitable anti-friction bearings in the bottom wall of the casing 25, and at their upper ends they bear in suitable anti-friction 100 bearings in an intermediate horizontal wall 50. Above this wall 50 is arranged the liquid transmission mechanism on the shaft 1 and the breaker mechanism surrounding the cam shaft 23, the two mechanisms being in 105 substantially the same horizontal plane. The turntable 51 carrying the breaker mechanism is pivoted to the wall 50 eccentrically of the axis of the shaft 23, the pivot being so located that the cam follower 52 will move 110 during the adjustment of the turntable upon its pivot in an arc of which the leading face of the cam as shown in Figure 3 is a chord. In other words the pivotal axis of the turntable is located in a line normal to the leading face of the cam in the position shown bisecting the line connecting the positions of the face of the cam follower in its two extremes of adjustment. As above pointed out adjustment of the cam follower along 120 this line serves merely to regulate the electrical dwell.

If the cam follower is moved nearer to the peak of the cam lobe, as it should be with an increase of engine speed, it is manifest that the breaker contacts 53 and 54 are held open for a less portion of the period of actuation of the cam follower by each cam lobe. Assuming for instance that in the position of the cam follower shown 130

in Figure 3 the cam follower is held raised and the contact thereby broken for 45 degrees of the 60 angular degrees of each lobe, it follows that the contacts are closed for 5 15 degrees, which is the period of electrical dwell. At slow engine speeds this 15 degrees is sufficient to fully energize the coil, but in order to maintain the time of dwell substantially constant as the speed of the 10 engine increases, it is necessary to increase the angular distance of the dwell which necessitates a corresponding decrease in the portion of the open position of the contacts.

This regulation is effected by swinging 15 the turntable 51 in a clockwise direction about its pivot. The turntable 51 is normally held against a stop 55 by a spring 56, which is the position of the least angle 20 of electrical dwell. To swing the turntable in a clockwise direction upon its pivot against the tension of the spring 56 as the speed of the engine increases, operating means are provided which are actuated by the secondary member 4 of the liquid 25 transmission device. In the construction shown these means comprise a pivoted lever 57, one end of which is in the path of an abutment 58 on the secondary member 4 and the other end of which carries a depending roller 59 30 in position to engage and actuate the turntable. The lever 57 is normally retracted against a stop 60 by a spring 61.

The lever 57 is also arranged in control 35 of the primary ignition circuit. A spring contact 62 in this circuit is adapted to engage the insulated conductor strip 63 on the turntable which carries the stationary breaker contact 54 and thereby completes the ignition circuit from the battery 64, conductor 65, spring contact 62, conductor strip 63, breaker contacts 54 and 53, spring arm 66, insulated plate 67 and conductor 68 to ground. When unrestrained the resiliency 40 of the spring contact 62 will cause it to break contact with the strip 63, as shown in Figure 3. The initial movement of the lever 57 causes the roller 59 to bear against the end of the spring contact 62 and press it into engagement with the strip 63 and 45 thereby close the primary circuit, and the retraction of the lever 57 under the influence of the spring 61, which immediately occurs when the engine stops, permits the spring contact 62 to spring back and open the 50 primary circuit, thereby conserving the battery supply when the engine is not running. This feature of my invention is described and claimed in my said co-pending application Serial No. 314,643.

60 The liquid transmission device is made sufficiently sensitive to effect the closing of the primary circuit as above described at lowest engine speed, while a substantial increase in engine speed is required to overcome the additional tension of the spring 65

56 and effect a rotative movement of the turntable 51. When this critical engine speed is attained, the drag upon the secondary member 4 is sufficient to cause the abutment 58 to swing the lever 57 about on 70 its axis and thus rotate the turntable 51 in the direction to move the operating face of the cam follower obliquely from the center of the cam along the line above described, while the spring 56 retracts the turntable 75 as the speed of the engine and consequently the pressure of the roller 59 upon the spring contact 62 decreases. In this way the breaker mechanism is adjusted through 80 mechanism responsive to the speed of the engine.

The lever 57 also operates as a lock-out to prevent the actuation of the starter while the engine is running, this feature being the subject matter of divisional application 85 Serial Number 347,411, filed December 26, 1919. In the form shown the starter lever 69 operates a pivoted lever 70 carrying a knife contact 71 and having an extension 72 beyond the pivot. The lever 57 has a nose 73 which in the retracted position in the lever is out of the path of the projection 72, but the first slight movement of the lever 57 under the influence of the abutment 58 causes the nose 73 to move into the path 95 of the projection 72 and thereby prevent the actuation of the starter lever 69 while the engine is running. To supply ignition for starting at the time when the projection 72 is under the nose 73 and thus locks 100 out the lever 57, there is provided a suitable shunt or branch circuit 63^a, as shown, between the battery and the conductor strip 63 including a manually operated switch or contact button 62^a, and this shunt circuit 105 will be closed while the engine is being cranked.

In the illustrated system the lever 57 also controls the lighting circuit as shown in Figure 3, to effect an automatic dimming of the 110 light when the engine is not running and to effect full illumination when the engine is running. For this purpose the manual switch 74 will be placed in contact with stationary contact 75, and the circuit is so arranged that the resistance 76 will be included in the light circuit when the engine is not running and will be excluded when the engine is running. The movement of the spring contact 62 against its bias by the 115 lever 57 also closes contact with the spring contact arm 77. It will be observed that when contact is broken between the members 62 and 77, which is the condition when the engine is not running and the lever 57 is 120 retracted the circuit through the lamps is as follows: from the battery 64, the conductor 65, conductor 78, resistance 76, conductor 79, switch 74, contact 75, conductor 80 and conductor 81 through the lamps 82 in 125 130

parallel to ground. Since this circuit includes the resistance 76 the lights will be dim. When the engine is running and the contact is closed between member 72 and

5 77, the circuit through the lamps is as follows: from battery 64, through conductor 65, contacts 62 and 77, conductor 79, switch 74, contact 75 and conductors 80 and 81 through the lamps to ground. Since this 10 circuit does not include the resistance 76, the lamps will be bright.

If this automatic dimming feature is not desired, the system includes the usual manually controlled lighting circuit. For this 15 purpose the switch 74 may be made to bridge the segmental contact 83 and either the stationary contact 84 and 85, the latter of which is connected to the conductor 80 while the two are connected by the resistance 86. If

20 it is desired to dim the lights the switch 74 is turned to the contact 84, the lighting circuit then being as follows: from battery 64 through conductors 65 and 78, segmental contact 83, switch 74, contact 84, resistance 25 86, contact 85, and conductors 80 and 81 through the lamps in parallel to ground. If it is desired to give the lamps full illumination the switch 74 is turned to the contact 30 85, whereupon the lighting circuit is the same as previously described with the exception of the exclusion of the resistance 86. This lighting system forms the subject matter of divisional application Serial No. 347,412, filed December 26, 1919.

35 In the modification shown in Figure 11, the pivotal axis of the turntable 51 is so located that the angular movement of the turntable regulates both the occurrence of the spark and the relative angle of electrical dwell, which construction is described and claimed in the said co-pending application of James C. Anderson, Serial Number 319, 40 092. In this construction the movement of the operating face of the cam follower as the turntable is swung about its pivot is along a diagonal line at an angle to the tangent to the cam periphery less than that of the leading face of the cam lobe. Since the adjustment of the turntable regulates 45 both the occurrence of the spark and the relative angle of electrical dwell, the automatic governor construction shown and above described with reference to Figures 3 to 10, inclusive, is unnecessary and will 50 therefore not be included in this construction. Instead the cam shaft 23 will carry the worm wheel 35 and will be driven directly by the worm 30. The breaker cam 87 shown in this construction is of the type 55 described and claimed in the said co-pending application of James C. Anderson, in which the leading face is at a greater angle to the tangent to the cam periphery than is the trailing face. It is clear that as the 60 lever 57 is swung about its pivot by the

abutment 58 it will first close the contact between the members 62 and 63, thus closing the primary ignition circuit, and will thereafter rotate the turntable 51 more or less in a counter clockwise direction against the 70 tension of the spring 56, thereby effecting the regulation of the spark and electrical dwell above described. The first movement of the turntable will cause a spring arm 88 to engage a stationary pin 89 which is carried by the wall 50 and protrudes through a slot 90 in the turntable. A continued movement of the turntable produces tension upon this spring arm, causing it to resiliently press the bearing member 91 on 80 top of the spring arm 92 which carries the cam follower and the movable breaker contact, and thus create increasing spring tension to hold the contacts closed as the speed of the engine increases. This feature of 85 my invention, which is described and claimed in my co-pending application Number 314, 643, has the merit of providing at all times only the closing tension for the contact that is required to overcome the inertia of the 90 movable parts sufficiently quickly to allow the contacts to close at the different engine speeds, and eliminates the wear upon the parts which is incident to constructions in which a spring of uniform tension is used, 95 since in such a construction the spring must manifestly be strong enough to close the contacts at the highest engine speeds, and therefore supplies a surplus of closing tension for low engine speeds. 100

It is obvious that my invention is in no wise limited to the particular construction illustrated in the drawings and above particularly described, but that it may be variously otherwise embodied within the scope 105 of my invention as pointed out in the appended claims.

I claim:

1. For an internal combustion engine, a breaker mechanism comprising a rotative 110 breaker cam, a breaker system including a pair of breaker contacts in an ignition circuit, one of the contacts being movable, and a cam follower arranged to control the movable contact, an adjustable supporting plate 115 for the breaker system, a primary member driven at a speed commensurate with that of the engine, and a secondary member arranged to have a drag imparted to it by the primary member and operatively connected 120 to the supporting plate to control the position thereof.

2. For an internal combustion engine, a breaker mechanism comprising a rotative breaker cam, a breaker system including a 125 pair of breaker contacts in an ignition circuit, one of the contacts being movable, and a cam follower arranged to control the movable contact, a supporting plate for the breaker system pivoted for angular adjust- 130

ment relative to the cam, a rotative primary member connected to be driven by the engine, and a rotative secondary member arranged to have a drag imparted to it by the 5 primary member and operatively connected to the supporting plate to control the angular position thereof.

3. For an internal combustion engine, a breaker mechanism comprising a rotative breaker cam, a breaker system including a 10 pair of breaker contacts in an ignition circuit, one of the contacts being movable, and a cam follower arranged to control the movable contact, a supporting plate for the breaker system pivoted for angular adjustment 15 relative to the cam, a rotative primary member connected to be driven by the engine, a rotative secondary member in proximity to the primary member operatively 20 connected to the supporting plate and biased in one direction, and a liquid coupling the two members and operative to transmit a torque from the primary member and cause the secondary member to rotate against its 25 bias.

4. For an internal combustion engine, a breaker mechanism comprising a rotative breaker cam, a breaker system including a 30 pair of breaker contacts in an ignition circuit, one of the contacts being movable, and a cam follower arranged to control the movable contact, a supporting plate for the breaker system pivoted for angular adjustment relative to the cam, resilient retractile 35 means influencing the supporting plate to a biased angular position, a shaft connected to be driven by the engine, a cup member operatively connected to the shaft, a liquid contained in the cup member, and a rotative sec- 40 ondary member in proximity to the cup member and coupled thereto by the liquid and having operative connection with the supporting plate to move the same against its bias.

45 5. For an internal combustion engine, a rotative breaker cam driven by the engine, a cam follower operative to open and close an ignition circuit and adjustable in a path eccentric to the axis of the cam, a primary 50 member driven at a speed commensurate with that of the engine, and a secondary member arranged to have a drag imparted to it by the primary member and operatively connected to the cam follower to control the 55 position thereof.

6. For an internal combustion engine, a breaker mechanism comprising a rotative breaker cam, a breaker system including a 60 pair of breaker contacts in an ignition circuit, one of the contacts being movable, and a cam follower arranged to control the movable contact, a supporting plate for the breaker system pivoted eccentrically to the axis of the cam, a rotative 65 primary member connected to be driven by

the engine, and a rotative secondary member arranged to have a drag imparted to it by the primary member and operatively connected to the supporting plate to control the angular position thereof.

7. For an internal combustion engine, a breaker mechanism comprising an engine driven shaft and a rotative breaker cam having operative connection with the shaft and angularly adjustable with respect thereto, a breaker system including a pair of breaker contacts in an ignition circuit, one of the contacts being movable, and a cam follower arranged to control the movable contact, a supporting plate for the breaker system pivoted for angular adjustment relative to the cam, automatic means controlled by the speed of the engine for angularly adjusting the supporting plate about the cam, and means independent of said automatic means for angularly adjusting the cam relative to the shaft.

8. For an internal combustion engine, a breaker mechanism comprising an engine driven shaft and a rotative breaker cam having operative connection with the shaft and angularly adjustable with respect thereto, a breaker system including a pair of breaker contacts in an ignition circuit, one of the contacts being movable, and a cam follower 95 arranged to control the movable contact, a supporting plate for the breaker system pivoted for angular adjustment relative to the cam, automatic means controlled by the speed of the engine for angularly adjusting 100 the supporting plate about the cam, and a second automatic means controlled by the speed of the engine for angularly adjusting the cam relative to the shaft.

9. For an internal combustion engine, a breaker mechanism comprising a drive shaft operated by the engine, a primary member thereon, a rotative secondary member arranged to have a drag imparted to it by the primary member, resilient means opposing 110 said drag, a breaker cam shaft adjacent the drive shaft, a supporting plate pivoted eccentrically to the axis of the breaker cam shaft, a breaker system carried by the supporting plate and including a pair of breaker contacts in an ignition circuit, one of the contacts being movable, and a cam follower arranged to control the movable contact, and connecting means between the secondary member and the supporting plate.

10. For an internal combustion engine, a breaker mechanism comprising a drive shaft operated by the engine, a primary member thereon, a rotative secondary member arranged to have a drag imparted to it by the primary member, resilient means opposing 115 said drag, a breaker cam shaft adjacent the drive shaft, a sleeve member surrounding the breaker cam shaft and connected to be driven by the engine, a centrifugal member 120

carried by the sleeve and operative to transmit rotation from the sleeve to the breaker cam shaft and to impart angular movement to the breaker cam shaft relative to the sleeve, a supporting plate pivoted eccentrically to the axis of the breaker cam shaft, a breaker system carried by the supporting plate and including a pair of breaker contacts in an ignition circuit, one of the contacts being movable, and a cam follower ar-

ranged to control the movable contact, and connecting means between the secondary member and the supporting plate.

In witness whereof I subscribe my signature in the presence of two witnesses.

RICHARD VARLEY.
